CANTILEVER SUPPORT SHELF BRACKET

Lee Boltin, 50 W. 96th St., New York, N.Y.

Filed Mar. 11, 1965, Ser. No. 84,213

Term of patent 7 years

(Cl. D54—1)

FIG.1

FIG.2

FIG.3

FIG.4

FIGURE 1 is a perspective view of a cantilever support shelf bracket embodying my new design.

FIGURE 2 is an end elevational view of the support bracket.

FIGURE 3 is a top plan view of the support bracket, and

FIGURE 4 is a side elevational view of the support bracket.

I claim:

The ornamental design for a cantilever support shelf bracket, as shown.
